UNITED STATES PATENT OFFICE.

GEORGE F. BLAKE, OF BOSTON, MASSACHUSETTS.

IMPROVEMENT IN VALVES FOR STEAM-ENGINES.

Specification forming part of Letters Patent No. 123,669, dated February 13, 1872; antedated January 29, 1872.

I, GEORGE F. BLAKE, of Boston, county of Suffolk, Commonwealth of Massachusetts, have invented an Improved Valve for Steam-Engines, of which the following is a specification:

Nature and Object of Invention.

My invention relates to the form of valve known as the cylindrical slide-valve, and has for its object the prevention of leakage between the ports when the valve shall have become worn by use. The cylindrical slide-valve is usually formed of a number of pistons connected by a cylindrical center piece of less diameter, the pistons being of the right width of face and placed the proper distance apart to form the valve.

My improvement consists in casting the longitudinal bridges *a a a* across the space between the pistons and turning the said bridges flush with periphery of the pistons. A sufficient number of these bridges are so arranged between the pistons that in whatever position

the valve is placed the port is inclosed between two of them, the valve being free to turn in its cylinder, and the only effect of wear is to perfect the joint between the cylinder and that part of the valve inclosing the port, so that no steam can leak from port to port.

In the drawing accompanying these specifications, Figure 1 is a side view and Fig. 2 a cross-section of my improved valve.

I claim as my invention—

The arrangement of bridges *a a a* upon a cylindrical slide-valve, when constructed and operated substantially as and for the purpose mentioned.

The above specification signed and witnessed at Washington this 10th day of June, A. D. 1871.

GEO. F. BLAKE.
